UNITED STATES PATENT OFFICE.

WILLIAM MILES, OF TORONTO, CANADA.

DESIGN FOR A GAME-BOARD.

SPECIFICATION forming part of Design No. 29,321, dated September 6, 1898.

Application filed July 7, 1898. Serial No. 685,350. Term of patent 7 years.

To all whom it may concern:

Be it known that I, WILLIAM MILES, a subject of Her Majesty the Queen of Great Britain, and a resident of the city of Toronto, in the county of York, in the Province of Ontario, Canada, have invented and produced a new and original Design for a Game-Board for the Game of Klondike, of which the following is a specification, reference being had

10 to the accompanying drawings, forming part thereof.

The drawings represent, in Figure 1, a plan view of my game-board, and in Fig. 2 a cross-sectional view of the same.

15 As shown in the drawings, the leading or material feature of my design consists of a rectangular game-board provided with a center surface A and circular counting-rings at

each corner B, subdivided, as shown. From the center of the central playing-surface extends radial lines dividing the circle into a series of sectors a, intermediate of the length of which are concentrically arranged in a ring a' the flags of different nations. A substantially semicircular starting-space C, as shown, is provided opposite the British and American flags.

Having described my invention, what I claim as new, and desire to secure by Letters Patent, is—

20 The design for a game-board as herein shown and described.

30 WILLIAM MILES.
